UNITED STATES PATENT OFFICE.

JOHN M. NESS, OF PHILADELPHIA, PENNSYLVANIA, ASSIGNOR OF FORTY-NINE ONE-HUNDREDTHS TO WALTER L. LORD, OF PHILADELPHIA, PENNSYLVANIA.

ENVELOP.

1,044,563.

Specification of Letters Patent. Patented Nov. 19, 1912.

Application filed November 15, 1911. Serial No. 680,383.

To all whom it may concern:

Be it known that I, JOHN M. NESS, a citizen of the United States, residing at Philadelphia, in the county of Philadelphia and State of Pennsylvania, have invented certain new and useful Improvements in Envelops, of which the following is a specification.

My invention relates to improvements in envelopes, and more particularly to envelopes having improved means for locking them in closed position, preventing any possibility of access to the contents of the envelop without detection.

A further object is to provide an improved safety fastener for envelopes which comprises two members, one connected with the body of the envelop, and the other with the closing flap and adapted to interlock when a blow is had upon the members when together, so as to permanently seal the envelop and prevent any possibility of the same being fraudulently opened without detection.

With these and other objects in view, the invention consists in certain novel features of construction and combinations and arrangements of parts, as will be more fully hereinafter described and pointed out in the claim.

In the accompanying drawings: Figure 1, is a plan view of my improved envelop showing the same in open position. Fig. 2, is a view in longitudinal section on an exaggerated scale showing my improved fastener as the members appear when brought together. Fig. 3, is a view similar to Fig. 2 showing the members after a blow is had upon the upper member to securely lock the members together. Fig. 4, is a perspective view of the member which is attached to the envelop flap. Fig. 5, is a perspective view of the member which is attached to the body of the envelop, and Fig. 6, is a plan view of the envelop blank.

Referring particularly to Fig. 6, it will be seen that my improved envelop comprises a blank 1, having end flaps 2 and 3, and a back flap 4, as well as a covering flap 5. The end flap 2 is provided with a tab 6, and the covering flap 5 is also provided with a tab 7 for purposes which will hereinafter appear.

My improved fastening device comprises two members 8 and 9. The member 8 is

composed of sheet metal, and is provided with two angularly positioned tongues 10 which project from a point adjacent the center of the member 8, and flare apart having their free ends bent forming rounded enlargements 11.

The member 8 is positioned against the inner face of the covering flap 5, and the tongues 10 project through an opening 12 in the tab 7, said tab 7 being preferably mucilaged so as to adhere to the member 8 and the covering flap 5 to securely hold the member 8 in position. The member 9 is also composed of sheet metal, and is provided at its ends with two inwardly projecting jaws 13, which are bent in a general compound curve as shown clearly in Figs. 2 and 5. Between these jaws 13, an inclined deflecting enlargement 14 is provided, and these jaws 13 project through an opening 15 in end flap 2, while the member is securely held against this end flap by the tab 6 which is mucilaged as shown. The jaws 13 also project through openings 16 and 17 in end flap 3, and back flap 4 respectively, and the back flap 4 is mucilaged as shown at 18 to seal the body of the envelop as is ordinarily done. The flap 5 is also mucilaged as shown at 19 to seal the flap in the ordinary way.

When the inclosures of the envelop are in place, it is simply necessary to fold the flap 5 downwardly after its mucilaged portion 19 is moistened. The tongues 11 of member 8 will position themselves between the jaws 13 of member 9, the respective tongues being at opposite sides of the enlargement 14.

When a sharp blow is had upon the flap, the tongues 12 will move outwardly under the jaws 13, and the jaws 13 and the tongues 10 will be mashed flat as shown in Fig. 3. The fastener will therefore securely hold the flap in its closed position, so that it can be removed without detection. Furthermore, as the fastener locks all of the flaps together, none of them can be removed without detection. Hence, while my improved fastener serves to lock the closing flap, it also acts to permanently secure all of the flaps of the envelop together, and when the members are locked together as shown in Fig. 3, the inclosures may be safely transported without the danger of fraudulent manipulation of the envelop.

Various slight changes might be made in

the general form and arrangement of parts described without departing from my invention, and hence I do not limit myself to the precise details set forth, but consider myself at liberty to make such changes and alterations as fairly fall within the spirit and scope of the appended claim.

Having thus described my invention, what I claim as new and desire to secure by Letters Patent is:

In combination with an envelop, a fastener hid entirely by the covering flap of the envelop when the envelop is sealed, said fastener comprising two members, one member comprising a base plate, an integral strip at each end of the base plate, said strips bent inward toward each other, positioned above the base and having rounded ends, said base plate positioned between the envelop front and the back flap of the envelop, and said rounded ends of the strips positioned in openings in said back flap and the end flaps, the other member comprising a base plate, an integral strip cut in from each end of the base plate and bent back upon the same,

said strips then bent downwardly and outwardly forming tongues and having their ends rounded, said tongues projected through an opening in a tab on the cover flap, said rounded ends on the strips of the last-mentioned member positioned between the rounded ends on the strips of the first-mentioned member, the base plate of the first-mentioned member bent outwardly and centrally between its ends forming a deflecting enlargement, presenting inclined faces to the tongues on the last-mentioned member, whereby the said tongues are projected outwardly under the strips of the first-mentioned member when a blow is had upon the fastener and the members forced together, substantially as described.

In testimony whereof I have signed my name to this specification in the presence of two subscribing witnesses.

JOHN M. NESS.
